TUFTING MACHINE

Joseph K. McCutchen, Ellijay, Ga.

Application November 24, 1944, Serial No. 564,938

6 Claims. (Cl. 112—79)

1

This invention relates to a combined looping and tufting machine and more especially to a machine having means for forming loops on the underneath side of a fabric and extending said loops downwardly and depositing them onto a looper bill where the loops are cut to form tufts.

It is an object of this invention to provide in a sewing machine, a needle bar equipped with a plurality of needles for sewing a plurality of rows of stitches in a fabric with looper members adapted to pass between the needles and the yarn carried thereby after the needles have penetrated the base fabric to engage the yarn and form loops and then to extend these loops downwardly to any desired length and then transfer these loops from the loopers onto a looper bill which has associated therewith a cutting knife so that some, but not all, of the loops on the looper bill will be cut upon each up and down movement of the needle to retain on the looper bill some of the loops in uncut condition to prevent the yarn from being pulled out of the fabric.

It is another object of this invention to provide a sewing machine having a plurality of needles and a plurality of loopers, there being one looper associated with each needle for engaging the yarn carried by the needle after the needle has pierced the fabric and extending the yarn downwardly to form an elongated loop together with an oscillating looper bill associated with each needle and adapted to pass into the loop while held by the loopers and to receive the same and the loopers will then move out of the loops and be ready to engage another set of loops being formed by the downwardly descending needles, while at the same time, the looper bills which have knives associated therewith will cut some, but not all of the loops held on the looper bills to thus form elongated tufts which is especially adaptable for making what is known as shag type of chenille bedspreads, rugs, and the like.

Some of the objects of the invention having been stated, other objects will appear as the description proceeds when taken in connection with the accompanying drawings, in which—

Figure 1 is a front elevation of my improved sewing machine, showing certain parts broken away for sake of clearness and showing the presser foot in raised position;

Figure 2 is a transverse sectional view taken along a line 2—2 in Figure 1 and showing the inter-connecting means between the shaft carrying the looper bills and the shaft carrying the knives for cutting the loops carried by the looper bills;

2

Figure 3 is a bottom plan view of the structure shown in Figure 1;

Figure 4 is a transverse sectional view taken along the line 4—4 in Figure 1;

Figure 5 is a vertical sectional view taken along the line 5—5 in Figure 4;

Figure 6 is a horizontal sectional view taken along the line 6—6 in Figure 4 and omitting the knife;

10 Figure 7 is a view taken along the same line as Figure 4, but showing the parts in a different position;

Figure 8 is a vertical sectional view taken along the line 8—8 in Figure 7.

15 Referring more specifically to the drawings, the numeral 10 indicates the uprising portion of a conventional sewing machine which has a conventional bed plate 11 and a goose-neck 12 which is an extension of the upriser 10 and on the free

20 end of the goose-neck 12 there is a head portion 13 which houses a vertically reciprocating needle bar 14 and a presser bar 15. The needle bar 14 has a transversely disposed bar 16 secured on the lower end thereof in which a plurality of needles 25 are disposed, said needles having an eye 18 in the lower end thereof through which a strand of yarn 23 passes.

25 The needle bar 14 is reciprocated vertically in a conventional manner and the pressure bar 15 is of conventional design and has a conventional pressure foot member 20 secured on its lower end to which presser foot 21 is pivotally secured as at 22.

30 There is one strand of yarn for each needle 35 which strands are omitted in Figure 1 for sake of clearness. These strands pass through conventional tension mechanisms 25 secured on a plate 26, which, in turn, is secured to the head 13 of the sewing machine. The head 13 of the 40 sewing machine also has a bar 27 secured thereon having a plurality of holes therethrough, through which the yarn passes after passing through the tension means 25 on its way to the needle eye 18 of the needles 17.

45 The sewing machine has a drive shaft 30 mounted in a conventional manner and having a hand wheel 31 thereon, and also a pulley 32 which is adapted to receive a suitable belt, not shown, which is connected to a suitable prime 50 mover, such as an electric motor, not shown, for driving the machine.

The shaft 30 has an eccentric portion 33 secured thereon on which the forked upper end of a connecting rod 34 has sliding movement and 55 this eccentric 33 gives a swinging movement to

the rod 34 as well as up and down movement due to the fact that to rod 34 there is pivotally connected, as at 35, a link 36 whose free end is connected to the free end of the link 37 which in turn is pivoted as at 38 to a stud on the inside of the uprising portion 10.

The lower end of rod 34 is pivotally connected to the free end of a lever 40 which is adjustably secured on rear feed rod 41 which is mounted at its ends for oscillation on suitable lugs 42 and 43.

Also on drive shaft 33 is an eccentric portion 45 which is surrounded by the upper end of a connecting rod 46, whose lower end is connected to the free end of an arm 47 fixed on front feed dog rod 48. The front feed dog rod 48 is mounted for oscillation at its ends on pivot screws 49 and 50 and has adjustably secured thereon arms 52 and 53 which project upwardly and rearwardly and have pins 57 therein which are adapted to have sliding movement in slotted portions 56 on the front end of a feed dog member 55. The rear end of the feed dog member 55 is pivotally secured as at 54 in arms 58 projecting upwardly from the rear feed dog rod 41. This feed dog member 55 has upwardly projecting portions 60 which are notched in their upper surfaces and are adapted to extend through suitable slots in a throat plate 61 fixed on top of the bed plate 10, and a suitable fabric 62 is adapted to pass between the presser foot 21 and the throat plate 61 for penetration by the needles when the presser foot 21 is in lowered position, however, the presser foot for sake of clearness is shown in raised position in all figures of the drawings.

Pivotally mounted on pivot screws 65 and 66 is a looper shaft 67 which has an arm 68 extending therefrom to which the lower end of a connecting rod 69 is pivoted. The upper end of connecting rod 69 surrounds a suitable eccentric 70 on the main drive shaft 30 which imparts oscillation to the looper shaft 67. The looper shaft 67 has adjustably secured thereon a plurality of looper members 71 each of which has a suitable hook 72 on its free end adapted to pass between a lowered needle and the strand carried thereby for forming a loop as shown in Figures 4 and 7. In Figure 7 the hook portion 72 of the looper 71 is shown entering between the needle and the strand carried thereby, whereas in Figure 4 the needle has moved downwardly to a position to where the looper bills, to be presently described, can pass into the loop so that the looper 71 can move upwardly and backwardly to its original position out of the loop.

Also fixed on shaft 30 is a suitable eccentric 75 which is surrounded by the upper end of a connecting rod 76 which has its lower end pivotally connected as at 77 to a lever 78 adjustably secured on looper bill shaft 80 which is mounted at its ends for oscillation on pivot screws 81 and 82. This looper bill has adjustably mounted thereon a plurality of members 83, these members being split and held in clamping relation on the shaft 80 by means of screws 84. Also adjustably mounted in members 83 is a rod 85 by means of a set screw 86 which extends upwardly and, as will be observed in Figure 8, has welded or otherwise secured to its upper end, a looper bill shank 87 which has a forwardly projecting looper bill 88 which has a downturned end for engaging and holding the loops transferred thereon by the looper members 71. The looper bill shaft 80 has fixedly secured thereto an arm 90 which has pivoted at its free end a

link 91 whose other end is pivoted as at 92 to a lever 93 adjustably mounted on a cutter shaft 94 mounted at its ends for oscillation on pivot screws 95 and 96. This cutter shaft 94 has mounted therein a plurality of rods 97, each of which has a slot 98 therein for receiving the lower end of a cutter knife 99 and surrounding the rods 99 are sleeves 100 which are adapted to be pressed against the edge of each cutter member 99 to confine it to an adjusted position by means of a screw 101 being threadably mounted in the free end of the rods 99. It is to be observed that the upper end of the cutter member 99 is sharpened and is flexed to have a rubbing engagement with the shank 87 and a portion of the looper bill 88 to cut the rearmost loops on the looper bill 88, but to fail to cut the foremost loops on the looper bill at all times.

Method of operation

The operation of the machine is as follows: As the needles approach lowermost position the looper hooks 72 start moving downwardly and rearwardly in between the needles and the strand carried thereby, and the looper bills 88 are moving rearwardly and the knives 99 are moving upwardly to cut the loops on the looper bills 88. By the time the needles have reached uppermost position the loopers 71 will have reached lowermost position slightly below the path of the looper bills 88, and the looper bills 88, as the needles reach uppermost position, start moving forwardly above the hooks 72 of the loopers to engage the loops as shown in Figure 4 and the looper bills 88 continue moving forwardly while the loopers 72 start moving upwardly as the needles start descending. The looper bills 88 continue their rearward movement until the needles have reached lowermost position and continue such rearward movement until the needles have reached uppermost position and the looper bill 72 have reached lowermost position, at which time the looper bills 88 start moving forwardly again.

Especial emphasis is placed on the fact that all of the shafts 41, 48, 67, 80 and 94 are driven directly from the main drive shaft 30. In previous machines of this type the feed shafts 41 and 48 have been driven from the main shaft and the looper and cutter mechanism has been driven either from the feed shafts or complicated power take-offs from the main shaft or a separate source of power has been used to drive the looper and cutter shafts. I eliminate all these complicated and unsatisfactory driving means by having eccentrics on the main shaft and connecting rods extending from the eccentrics to the looper and cutter shafts for operating the same positively and without any lost motion.

In the drawings and specification, there has been set forth a preferred embodiment of the invention, and although specific terms are employed, they are used in a generic and descriptive sense only and not for purposes of limitation, the scope of the invention being defined in the claims.

I claim:

1. In a sewing machine having a vertically reciprocating needle for carrying a strand through a base fabric, an oscillating looper adapted to pass between the needle and the strand carried thereby for forming a loop on the lower surface of the fabric as the needle moves upwardly through the fabric, an oscillating looper bill pointing in the opposite direction from the looper and adapted to pass into the loop while it is held

on the looper while the looper is in lowered position and to hold the same while the looper moves upwardly and out of the loop, and cutting means associated with the looper bill for cutting some but not all of the loops held on the looper bill upon each complete oscillation of the looper bill.

2. In a sewing machine having a vertically reciprocating needle for carrying a strand through a base fabric, an oscillating shaft mounted below the fabric and in front of the needle, and having a looper arm mounted thereon for swinging downwardly and rearwardly between the needle and the strand carried thereby while the needle is in lowered position for forming and elongating a loop from the strand carried by the needle, an oscillating looper bill disposed below and rearwardly of the looper for passing into the loop held by the looper while the looper is in lowermost position, and cutting means associated with the looper bill for cutting some but not all of the loops on the looper bill upon each oscillation of the looper bill.

3. In a sewing machine having a vertically reciprocating needle bar carrying a plurality of vertically disposed laterally spaced needles, each needle being adapted to carry the strand through a base fabric, an oscillatable shaft disposed below the fabric and in front of the needle, said shaft having a plurality of looper arms mounted thereon each having a hook on their rear ends adapted to pass between the needle and the strand carried thereby while the needle is in lowered position, said looper arm being adapted to move the loops downwardly to a further elongated position than the depth to which the needle eye descends below the fabric, a second oscillatable shaft disposed below and rearwardly of the first oscillatable shaft and having a plurality of looper members mounted thereon, the looper members having a looper bill on their upper ends pointing in the opposite direction to that of the looper arms and adapted to swing forwardly into the loops while they are held by the looper arms in their lowermost position to engage the loops and hold the same while the looper arms move upwardly and forwardly out of the loops, a third oscillatable shaft having a plurality of cutter knives mounted thereon, there being one cutter knife for each of the looper bills, and the upper end of the cutter knives having sliding engagement with the looper bills for cutting some but not all of the loops off of the looper bills upon rearward oscillation of the looper bills.

4. In a sewing machine having a vertically reciprocating needle for penetrating a base fabric and carrying a strand therethrough, an oscillating looper member disposed below the fabric and adapted to pass between the needle and the strand carried thereby and engage the strand and form a loop as the looper member moves downwardly and as the needle moves upwardly through the fabric, said oscillating looper being adapted to move downwardly below the lowermost point to which the needle descends to further elongate the loop, an oscillating looper bill adapted to pass into the loop while it is held by the looper member in its lower most position and to hold the loop while the looper member moves upwardly out of the loop, and cutting means associated with the looper member for cutting some but not all of the loops held on the looper bill during each oscillation of the looper bill.

5. In a sewing machine having a vertically re-

ciprocating needle bar carrying a plurality of vertically disposed laterally spaced needles, each needle being adapted to carry the strand through a base fabric, an oscillatable shaft disposed below and in front of the needle, said shaft having a plurality of looper arms mounted thereon having a hook on their rear ends adapted to pass between the needle and the strand carried thereby while the needle is in lowered position, said looper arm being adapted to move the loops downwardly to a further elongated position than the depth to which the needle eye descends below the fabric, a second oscillatable shaft disposed below and rearwardly of the first oscillatable shaft and having a plurality of looper members mounted thereon, each of the looper members having a forwardly directed looper bill on its upper end adapted to swing forwardly into the loops while they are held by the loopers in their lowermost position to engage the loops and hold the same while the looper members move upwardly and forwardly out of the loops, a third oscillatable shaft having a plurality of cutter knives mounted thereon, there being one cutter knife for each of the bills, and the upper end of the cutter knives having sliding engagement with the looper bills for cutting some but not all of the loops off of the looper bills upon rearward oscillation of the looper bills, the first two oscillatable shafts each having an arm fixed thereon, a connecting rod having its lower end connected to an arm, a main drive shaft having a plurality of eccentrics thereon, the upper end of each connecting rod being mounted on one of said eccentrics for imparting oscillation to the first two named oscillatable shafts.

6. A sewing machine having a feed side and a discharge side and a vertically reciprocating needle for carrying a strand through a base fabric, an oscillatable shaft disposed below the fabric, and having a looper thereon extending towards the discharge side of the machine for passing between the strand and the needle when the needle is in lowered position for forming loops on the lower side of the fabric, a second oscillatable shaft having a looper bill mounted thereon and extending towards the feed side of the machine, and adapted to pass into the loop held by the looper while the looper is in lowered position to engage and hold the loop while the looper moves upwardly out of the loop, a third oscillatable shaft mounted below the fabric and having a cutter member mounted thereon which is adapted to cut some but not all of the loops on the looper bill as the looper bill oscillates toward the discharge side of the machine, away from the looper from which it received its loop.

JOSEPH K. McCUTCHEON.
